UNITED STATES PATENT OFFICE.

ALBERT W. FRANKLIN, OF NEW YORK, N. Y., ASSIGNOR TO CHAS. FRESHMAN CO. INC.,
OF NEW YORK, N. Y., A CORPORATION OF NEW YORK.

VERNIER TUNING DIAL.

Application filed February 19, 1924. Serial No. 693,803.

This invention relates to improvements in dials and more particularly to the type of dial used in connection with electrical and like apparatus in which it is desirable to 5 obtain precision in setting.

Such accuracy in adjusting the dials had hitherto been attained by expensive and cumbersome methods, as for instance by the use of frictional or toothed gearing, in 10 involving a rotor pinion distinct from the dial, by slow and tedious screw adjustments necessarily limited in range of action, and divers other devices which disfigure the dial and mar the appearance of the panel to 15 which they are applied.

It is therefore the object of this invention to provide a particularly simple and effective device whereby a dial may be set or reset exactly to any desired point with 20 micrometer precision.

Another purpose is to produce means for adjusting the dial that are wholly unobjectionable in appearance and are incapable of injuring the dial or panel on which it is 25 mounted.

A further aim is in the provision of an adjusting means that can be readily operated without special experience and which in no manner interferes or conflicts with the free 30 and untrammelled twirling of the dial by its knob in obtaining an approximate setting.

These several aims and objects are accomplished by the novel and practical construction and combination of parts hereinafter 35 described and illustrated in the accompanying drawings, forming a material part of this disclosure, and in which:—

Fig. 1 is a bottom plain view of a dial made in accordance with the invention.

Fig. 2 is a transverse sectional view, taken 40 on line 2—2 of Fig. 1, shown as in operative position.

Fig. 3 is a fragmentary sectional view, similar to Fig. 2, but showing a slight modification in construction.

In all of the several views the numeral 10 designates a conventional panel or plate, through which extends a spindle 11 having 45 fixed to it whatever part is to be rotated into adjustment.

The opposite, outer end of the spindle is secured in a bushing or sleeve 12, usually made of brass and fixedly embedded in the central hub portion 13 of the dial.

55 This hub element is integral with the

convex face of a knob 14 having an annular recess 15, to reduce weight, the knob being plain or knurled as preferred, its lower end blending into the face 16 of the dial from which extends a beveled peripheral edge 17. 60

An annular ring 18 having a level outer surface is at the back of the bevelled edge 17, the ring enclosing a recess 19 into which the recess 15 opens, thus reducing the thickness, and correspondingly the weight, of the material of the dial, which may be of hard rubber, bakelite or similar dielectric substance. 65

The foregoing is substantially descriptive of any ordinary type of dial and it will be 70 understood that graduations, scales, numerals or other marks may be borne on the elements 16 and 17 as is usual.

In carrying out the invention, one or more radial, inreaching blocks 20 extend level from 75 the face of the ring 18 to an annular depression 21 in the back of the dial and formed through the block and face 16 is a narrow elongated slot 22, tangent to the axis of the dial. 80

A recess 24 extends into the bevelled portion 17 of the dial, at a point registering with the center of the slot 22, and extending from the recess 23 into the annular recess 21, parallel with the base of the dial, is an 85 opening in which is engaged a screw 24 or pin if preferred, acting as a pivot support for a roller 25.

The diameter of this roller and its position, is such that its periphery extends 90 slightly below the level of the base of the dial and also above the upper face 16, the roller being provided with a relatively soft rubber covering over its rounded edge for the double purpose of affording an effective 95 frictional contact with an operator's fingers in maneuvering it, and also to prevent marring the surface below the dial on which the roller impinges.

In the modification shown in Fig. 3, the 100 slot 22 in the face of the dial opens at the bottom into a rectangular recess 26 suited to receive short pintles or trunnions 27 extending axially from the sides of the roller 25 and maintaining the roller in operative 105 position in the slot 22 as before described.

In either case the operation is the same, the dial being quickly brought into approximately correct positions by twirling the knob 14 and then finely and accurately ad- 110

justed by placing finger on the roller and rotating it as may be necessary.

Although the foregoing is descriptive of specific embodiments of the invention, it will be understood that the appended claims will cover minor changes regarding the roller constructions, mounting, number used, sizes, proportions and like inconsequential details.

10 Having described my invention, what I claim as new and desire to secure by Letters Patent is:—

1. A dial having a depression or pocket in

its rear face adapted to receive the trunnions of a roller and having an elongated slot 15 through which said roller may operate.

2. The combination with a dial having a recess in its rear face, and a slot communicating therewith of a trunnioned roller journaled in said recess and extending 20 through said slot.

Signed at New York in the county of New York and State of New York this 4th day of February A. D. 1924.

ALBERT W. FRANKLIN.
